UNITED STATES PATENT OFFICE

2,441,982

BROOM STAND

Naomi A. Turner, Detroit, Mich.

Application September 25, 1946, Serial No. 699,305

4 Claims. (Cl. 248—210)

1

The invention relates generally to mops, brooms and the like and more particularly to an attachment which is adapted to be applied on the lower end of the handle of a broom, mop or similar implement to serve as a stand whereby the lower portion of the broom, mop or the like will be elevated or raised from the floor thereby preventing the straws of the broom from becoming bent by the weight of the broom.

An important object of the invention is to provide an inexpensive, durable and simple attachment which can be applied to a broom handle or the like and including legs which hold the lower end of the broom raised above the floor so that the broom may stand alone.

Another object of the invention is to provide means for holding the legs in an out-of-the-way position while the broom is being used.

A still further object of the invention is to provide a hand gripping device to facilitate raising and lowering of the legs of the stand.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the invention applied to a broom;

Figure 2 is a front elevational view thereof in its lowered position;

Figure 3 is a side elevational view;

Figure 4 is a sectional view taken on the line 4—4 of Figure 2 and with the broom removed;

Figure 5 is a fragmentary sectional view of one of the legs of the stand;

Figure 6 is a front elevational view of the invention as applied to a broom in a raised position, and

Figure 7 is a sectional view taken on the line 7—7 of Figure 2.

Referring now to the drawings in detail wherein for the purpose of illustration I have disclosed a preferred embodiment of the invention, the numeral 5 designates a handle of a broom, mop or similar implement which is constructed of wood, or other suitable material and the numeral 6 indicates the straw body of the broom, said body being secured to the lower end of the handle in any suitable manner.

Secured to the lower portion of the handle 5 is a bracket 7 comprising a horizontal flat surface 8 with an upwardly projecting ring 9 attached to said surface over a hole 8a formed therein. The flat surface 8 is rounded off at 10 and extends

2

downwardly to 11 where the ends 12 of the bracket are turned inwardly and spaced slightly from the opposite sides of the broom body.

A rivet 13 extends through the ring 9 and the lower end of the handle and the heads 14 of the rivet are then flattened or upset.

A broom body encircling band 15 is formed with four holes 16 and is held horizontally under the ends 12 of the bracket 7 and secured thereto in any suitable manner.

A vertically slidable ring 17 is positioned on the handle and to which a pair of spring biased clasps 18 and 19 are pivotally attached at the opposite sides of the broom handle.

15 A pair of inverted U-shaped legs 20 are positioned at opposite sides of the broom body including a cross-bar 21 at their upper end curved inwardly from the vertical axis of the legs and are welded or otherwise suitably secured to the ring 17.

The lower ends 22 of the legs are placed through the holes 16 in the body encircling band 15 for vertical sliding movement therein.

A hand grip or knob 23 projects from one side 25 of the ring 17 which affords an easy means for raising the ring 17 and legs 20. The legs are held in a raised position by the clasp 18 engaging an upper clasp retainer 24 which is fastened upwardly from the lower end of the handle.

30 When it is desired to support the broom in an upright position so that the body is raised from the floor the clasp 18 is disengaged from the clasp retainer 24 and lowering the legs 20 to engage the clasp 19 in a lower clasp retainer 25 fastened to the broom handle below the clasp retainer 24.

35 A rubber foot 26 is internally threaded and is secured on each lower end 22 of the legs to prevent the stand from slipping and also to prevent the legs from being pulled out of the body encircling band 15.

To place the device on a broom handle the ring 9 is slipped on the handle and secured adjacent its lower end with the body encircling band 15 positioned around the body of the broom. The rivets 45 13 secure the bracket and the body encircling band in a fixed position on the broom handle.

The slidable ring 17 with the legs 20 and the clasps 18 and 19 attached thereto is then slipped over the upper end of the handle and lowered so 50 that the ends of the legs extend through the holes 16 of the body encircling band. The clasp retainers 24 and 25 are then fastened to the sides of the broom handle at a point for engagement by the clasps 18 and 19, the clasp 18 supporting the stand in its raised position when it is desired

to use the broom in a normal manner and the clasp 19 securing the stand in its lowered position to rest on the floor and support the broom in an elevated position.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

What I claim as my invention is:

1. A broom stand adapted for attaching to a broom handle and comprising a broom body encircling band, a bracket carried by the broom handle and secured to the band, a ring slideable on the broom handle, a set of legs carried by the ring and slideable in the band, and means for holding the legs in vertically adjusted position relative to the broom.

2. A broom stand adapted for attaching to a broom handle and comprising a broom body encircling band, a bracket carried by the broom handle and secured to the band, a ring slideable on the broom handle, a set of legs carried by the ring and slideable in the band, upper and lower clasps carried by the ring, upper and lower clasp retainers fastened to the handle for engaging the respective clasps, and manual gripping means on the ring for raising the legs to engage the upper clasp with the upper clasp retainer and for low-

ering the legs to engage the lower clasp with the lower clasp retainer.

3. A broom stand adapted for attaching to a broom handle, and comprising a broom body encircling band, a bracket connecting the band to the handle, a ring slideable on the handle, a pair of inverted U-shaped legs attached at their upper ends to the ring, said band including guide means slidably receiving the legs, and means adjustably connecting the legs to the handle to secure the legs in a raised or lowered position relative to the broom body.

10 4. A broom stand adapted for attaching to a broom handle, and comprising a broom body encircling band, a bracket connecting the band to the handle, a ring slideable on the handle, a pair of inverted U-shaped legs mounted on opposite sides of the broom body and attached at their upper ends to the ring, said band including guide means 15 slidably receiving the legs, upper and lower clasps carried by the ring, and upper and lower clasp retainers fastened to the handle for engagement by the respective clasps to secure the legs in a raised or lowered position relative to the broom body.

25 NAOMI A. TURNER.
